UNITED STATES PATENT OFFICE.

HELGE A. BERLE, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY.

CONTROL MECHANISM FOR CONCRETE-MIXING APPARATUS.

Application filed April 14, 1928. Serial No. 270,056

The present improvements relate in general to concrete mixing apparatus and more particularly to charging means for such apparatus and control mechanism therefor.

5 In the art of concrete mixing and placing wherein freshly mixed concrete is mixed in situ and conveyed to the point of placement, it is of paramount importance to maintain a fixed ratio between the dry aggregates, cement, water, etc. Building and inspection requirements are rigidly enforced with respect to the proportions of the ingredients introduced into the mixer, with the consequent development of various types of measuring 10 tanks, hoppers, etc. to accurately predetermine the percentage of each ingredient for every given batch.

The employment of water measuring means normally entails the use of supply and discharge means therefor which may be so inadvertently and inadvertently operated as to destroy the measuring function of the receptacle, permitting an excess of water to reach the mixer. The present improvements have 15 as their object, among others, the provision of a control mechanism for water measuring devices whereby an excess over the predetermined amount of water is precluded from passing to the mixer. A further object resides in the provision of valves and control means therefor functioning in association with or independently of an operating means for the discharge of dry ingredients, compelling a sequential operation of the valves and precluding inadvertent or malicious actuation thereof.

Other objects will be apparent to those skilled in the art upon reference to the accompanying drawings, in which

40 Fig. 1 is a side elevation of a measuring receptacle embodying the present improvements;

Fig. 2 is a modification of a detail.

The water measuring tank or vessel 1 may 45 be suitably mounted on the mixer frame 2, preferably adjacent the mixer and hopper (not shown), although any convenient location facilitating flow from the tank to the mixer will suffice. Water supply conduit 3 and discharge conduit 4 are provided, and may have independent communication with the tank 1. As illustrated, however, a convenient assembly results in the employment

of a T section 5 uniting conduits 3 and 4, the longer leg of the section establishing communication between both conduits and the tank through port 6.

Control valves 7 and 8 are provided in the inlet and outlet pipes 3 and 4 respectively, and may be of any suitable type, although in the present embodiment, valves of the rotary plug design are employed. Automatic actuating means for the inlet valve 7 comprise an energized arm 9 suitably keyed to the plug of valve 7 for rotation therewith, a weight 10 being mounted on the longer branch of said arm. The lower surface of the opposite or shorter branch of said arm 9 is faced with a plate 11, for contact, in the illustrated position (full line) with a spring 12 suitably secured to a shoulder 13 on T section 5.

The inlet valve 7 is normally held open when arm 9 is in elevated or energized position, being restrained or locked in such position by a bail 14, pivoted to tank 1, defining a latch 15 normally engaged with nose 16 on the arm 9. In this position the weight 10 and compressed spring 12 stand energized to "kick" the arm 9 and valve 7 in a clockwise direction.

The outlet valve 8 is provided with a segmental gear 17, keyed to the plug of the valve for imparting rotation thereto. In the position illustrated, valve 8 is normally closed and is restrained or locked in such position by pivoted dog 18 in contact therewith. Said dog 18 has an integrally formed short arm 18' extending at an angle to the branch in contact with gear 17. As illustrated, this dog is loosely mounted for rocking movement on pivot 19, a coil or other spring 20 being provided for constantly urging dog 18 in a clockwise direction, for holding same in locking position with respect to gear 17.

From the description thus far, it is apparent that inlet valve 7 is normally locked in open position permitting free flow of water from pipe 3 to the tank to be measured, while discharge or outlet valve 8 is normally locked in closed position, precluding flow through pipe 4.

Mechanism for incepting a predetermined sequence of operations including closing inlet valve 7, locking same in closed position and simultaneously releasing the locking means for valve 8 and subsequent opening of said

valve is provided in control features now to be described. A hand lever 21 is suitably mounted for rocking movement about pivot 22, being provided at its inner end with a latch bar 23 for actuating a batch hopper door or gate. The device is accordingly adapted for use in an organization such as described and claimed in the copending application of James E. Bushnell, filed February 23, 1928, Serial No. 256,208. A segmental gear 24 is loosely mounted on pivot 22 adapted to engage gear 17 for rotating same. Arm 21 and gear 24 are operatively connected by a delayed action or lost motion means comprising a slot 26 and pin 25.

A rod 27, suitably mounted adjacent the tank, has the lower end thereof pivotally connected to arm 21 at 28, extends through guide or bracket 29 mounted on tank 1 or any other convenient support and terminates, as illustrated, with a cam 30 contacting pin 31 on latch 15. A coil spring 32 surrounds rod 27 and rests, at its base, upon bracket 29, and at its opposite end bears on the bifurcated end 33 of a latch bar 34. Spaced above said spring, a collar 35 is secured to the rod 27, as illustrated, so that the end 33 of bar 34, which embraces rod 27, is contacted on one side by spring 32 and on the other by collar 35.

As described, the latch 34 has one end bifurcated at 33, while the opposite end thereof is loosely pivoted for rocking movement about pivot 19. A recess 36 is suitably provided on latch 34 for engagement by nose 16 as hereinafter set forth.

In operation, the measuring means of the tank 1, having been set at the desired capacity, the inlet and outlet valves as well as the control mechanism are in the position illustrated in full lines. Accordingly, inlet valve 7 is locked open, outlet valve 8 is locked closed and latch bar 23 is down, holding the dry ingredients within the batch hopper (not shown). It is apparent, that manual depression of lever 21, will not impart movement to gear 24 until rod 27 has been first moved a substantial amount. Furthermore, gear 24 cannot function to actuate gear 17, to open valve 8 until lock 18 has been released. It is therefore obvious that no water can be discharged from tank 1 through pipe 4 to the mixer (not shown) until lock 18 is released, which release is dependent upon the closing and locking of the inlet valve 7, as will appear.

To discharge the measured water in tank 1, arm 21 is manually or otherwise actuated in a clockwise direction. During the initial movement thereof, rod 27 is raised and cam 30 thereon through pin 31 swings latch 15 about its pivot until free of nose 16, while at the same time collar 35 is raised to dotted line position and spring 32 urges latch 34 to dotted (horizontal) position. Accordingly

the arm 9 is now free to close valve 7. The spring 12, being under compression, supplements the gravity force of weight 10, and "kicks" arm 9 in a clockwise direction. It is to be noted that arm 18' of dog 18 is positioned in the path of moving arm 9 while catch 36 of latch 34 is disposed in the arc of travel of nose 16. As arm 9 approaches the dotted line position it contacts with arm 18' and throws dog 18 to dotted line position where it is out of contact with gear 17. Simultaneously with this operation, the nose 16 of arm 9 snaps into recess 36 of the now horizontally disposed latch 34, the spring 32 being retracted sufficiently to allow nose 16 to pass into recess 36, but immediately restoring bar 34 to horizontal or locked position. The dotted line position of these parts represents the valve 7 in closed position and it is apparent that an upward pull on arm 9 in a direction for opening valve 7 is impossible due to the locking relation of bar 34 and nose 16.

By the time the foregoing operations have been accomplished, the pin 25 is contacting the upper end wall of slot 26, and since dog 18 has been removed and valve 7 is locked in closed position, gear 17 is now free to move and subsequent movement of lever 21, raises latch 23, moves gear 24 which in turn actuates gear 17 and outlet valve 8 is opened permitting the measured water in tank 1 to discharge through conduit 4 to the mixer along with the dry ingredients from the batch hopper. Obviously, only the water from tank 1 discharges through pipe 4, and an excess amount direct from supply pipe 3 cannot be discharged through pipe 4 due to the fact that inlet valve 7 is locked closed. This feature of locking said valve while the discharge valve 8 is open, prevents inadvertent or malicious addition of water in excess of the measured quantity.

In order to again admit water to tank 1, it is necessary that discharge valve 8 be previously closed. This is accomplished by moving arm 21 in a counter clockwise direction thus closing valve 8 (through gears 24 and 17) and, at the same time rod 27 is lowered whereby collar 35 depresses and rocks latch 34 to the full line position releasing nose 16 on arm 9. The arm 9 is now free to be raised from dotted line to full line position. During this initial movement the pressure on arm 18' of dog 18 is withdrawn and said dog snaps into full line position (locking the gear 17) under the influence of spring 20. When arm 9 reaches full line position, valve 7 is again open and the latch 15 falls in position for holding said arm by nose 16.

Suitable guides similar to bracket 29 may be provided along rod 27 wherever desired. In the embodiment illustrated in Fig. 2, a modified form of locking means for holding inlet valve 7 closed, is depicted. All of the

features of the embodiment of Fig. 1 are retained, except the bracket 29 supporting spring 32. The drawing in Fig. 2 provides a collar 40 attached to rod 27 which supports spring 32. Obviously collar 40 and spring 32 move with rod 27. The operation of the improvements with this modified latch is the same as that of the embodiment first described with the added feature that when the 10 arm 9 is locked with valve 7 in closed position (i. e. when arm 9 is in dotted line position), further upward movement of rod 27, attending the opening of valve 8, causes compression of spring 32 (being resisted by the bifurcated end 33 of bar 34) thereby effecting a secure hold by bar 34 on nose 16. It is apparent that the further rod 27 moves, the more rigid the lock becomes, so that as long as lever 21 is down, holding valve 8 open, latch 20 34 is practically immovable.

From the foregoing, it is obvious that applicant has provided a control mechanism compelling a fixed sequence of operation and one in which, after the inlet valve is closed 25 and the outlet valve is opened, the latter must be closed before the former can again be opened.

Various modifications within the scope of the present improvements will be apparent to 30 those skilled in the art.

I claim.

1. In a device of the character described, the combination of a receptacle having inlet and outlet conduits, a normally open valve in 35 said inlet conduit, a normally closed valve in said outlet conduit, an energized actuating means for said inlet valve, an energizable actuating means for said outlet valve, means normally restraining each of said actuating 40 means, a normally inoperative lock for said energized means and a single control mechanism for initiating release of said restraining means, rendering said lock operative and operating said energizable means.

2. A water supply means for concrete mixing apparatus comprising a water tank having inlet and outlet conduits, a valve controlling each conduit, normally locked actuating means for each valve, a second lock for said 45 inlet valve actuating means, mechanism for releasing said inlet valve actuating means, said last named means subsequently releasing said outlet valve actuating means and becoming locked by said second lock, and means for operating said outlet valve actuating means.

3. In a device of the character described, a valve controlled conduit having a normally open valve, energized means for automatically closing said valve, releasable means restraining said energized means, a second valve controlled conduit having a normally closed valve, actuating means for opening said valve, releasable means restraining said 50 actuating means positioned for release by said energized means, means for automatically

locking said energized means in closed position, mechanism for releasing said first named releasable means, whereby said energized means closes said first named valve, releases said releasable means for said second 70 named valve and is automatically locked, and means operating in conjunction with said mechanism for opening said second named valve.

4. A water supply means for concrete mixing apparatus comprising a water tank having inlet and outlet conduits, a valve in each conduit, means locking said valves in predetermined positions, mechanism operable to successively release said locking 75 means, a second locking means for one of said valves positioned for locking said valve concurrently with the release of said other valve and means for actuating said other valve.

5. A water supply means for concrete mixing apparatus comprising a water tank having inlet and outlet conduits, a valve in each conduit, said inlet valve including energized operating means therefor, releasable means normally locking said outlet valve, 80 releasable means normally locking said inlet valve, means positioned for locking said inlet valve concurrently with the release of said outlet valve subsequent to the initial release of said inlet valve, and operating mechanism 85 for initially releasing said inlet valve and subsequently actuating said outlet valve.

6. The combination set forth in preceding claim 5, said last named locking means being operatively connected with said operating 90 mechanism.

7. A water supply means for concrete mixing apparatus comprising a water tank having inlet and outlet conduits, a valve in each conduit, said inlet valve including energized operating means therefor, releasable means normally holding said operating means in energized position, mechanism for releasing said releasable means and establishing locking means for said operating 100 means in a predetermined position, locking means for said outlet valve releasable by said operating means in said predetermined position, and actuating means for said outlet valve.

8. The combination set forth in preceding claim 7, said mechanism and actuating means being operatively connected.

9. A water supply means for concrete mixing apparatus comprising a water tank 120 having inlet and outlet conduits, a valve in each conduit, said inlet valve including energized operating means therefor, releasable means normally holding said operating means in energized position, mechanism for releasing said releasable means and establishing locking means for said operating 125 means in a predetermined position, locking means for said outlet valve releasable by said operating means in said predetermined position, 130

tion, actuating means for said outlet valve, said mechanism and actuating means having a delayed action connection.

10. A water supply means for concrete mixing apparatus comprising a water tank having inlet and outlet conduits, a valve in each conduit, said inlet valve including energized operating means therefor, releasable means normally holding said operating means in energized position, mechanism for releasing said releasable means and establishing locking means for said operating means in a predetermined position, locking means for said outlet valve releasable by said operating means in said predetermined position, actuating means for said outlet valve, said mechanism and actuating means having a delayed action connection, and means adapted to operate a batch hopper operatively connected with said mechanism.

11. A water supply means for concrete mixing apparatus comprising a water tank having inlet and outlet conduits, a valve in each conduit, said inlet valve including energized operating means therefor, releasable

means normally holding said operating means in energized position, mechanism movable in one direction for releasing said releasable means and establishing locking means for said operating means in a predetermined position and in another direction for disabling said locking means, spring actuated locking means for said outlet valve releasable by said operating means in said predetermined position, and actuating means for said outlet valve operatively connected with said mechanism.

12. In a device of the character described, a measuring tank having a normally open inlet valve and a normally closed outlet valve, operating means for said valves and interconnected control mechanism therefor compelling a sequence of operations comprising closing of said inlet valve, opening and closing of said outlet valve before subsequent opening of said inlet valve.

Witness my hand this 9 day of April, 1928,
county of Middlesex, State of N. J.

HELGE A. BERLE.
